[57] CLAIM

The ornamental design for a hanger for boat fender and the like, as shown and described.

DESCRIPTION

FIG. 1 is a top plan view of a hanger for boat fender and the like showing my new design;

FIG. 2 is a front elevational view thereof;

FIG. 3 is a right side elevational view thereof;

FIG. 4 is a left side elevational view thereof;

FIG. 5 is a bottom plan view thereof; and

FIG. 6 is a perspective view of a hanger for boat fender and the like showing an alternate form of my new design.

FIG. 1

FIG. 3

FIG. 2

FIG. 4

FIG. 5

FIG. 6
